RECORDER AND REPRODUCER

Allan P. Bloxson, Houston, Tex.

Application January 7, 1937, Serial No. 119,385

12 Claims.

(Cl. 179—6)

The invention relates to a sound recording and reproducing device and more particularly to a device for recording and repeating incoming messages during the absence of a telephone subscriber.

It is an object of the invention to provide a device that can be used in conjunction with a standard telephone set without modifying that set and without requiring any change in central office equipment.

It is also an object of the invention to provide a message recording and repeating system which will, through the normal use of central station equipment, transmit to any calling station the messages received during the absence of the subscriber.

A further object is to provide a message recording and repeating system to be used in conjunction with standard telephone equipment without the interposition of operative steps by a central station operator to effect the ultimate functioning of the system.

Other and further objects will be apparent from the following description taken in connection with the single figure of drawings which illustrates, in a preferred embodiment, the component mechanisms and constructions, together with the electrical connections whereby the above recited functions and objects are achieved.

In this description the term "station" is used to refer to one of the various conventional forms of telephone equipment provided a subscriber at his residence or place of business. In the accompanying drawing the invention is shown as used in conjunction with the so-called "French" type of telephone set, which is characterized by the unitary mounting of the transmitter 5 and the receiver 6, the weight of which is used to disconnect the telephone set from the line leading thereto from the telephone exchange. For convenience, the unitary transmitter and receiver will be herein referred to as a receiver except where the transmitter or receiver is specifically referred to as such.

The term "incoming call" includes the sequence of operations that includes ringing and the transmission and reception of an audible message. By "record" reference is made to any suitable instrumentality of recording the voice or other identifiable impulse such, for example, as engraving of phonic grooves in a disc or cylinder, production of a photographic track or the magnetic recording of sound impulses on a soft iron wire, such record bearing a message or messages

adapted to be reproduced by the device of the invention.

The general embodiment of the invention comprises a station including a multiple line ringer 1, to which is selectively connected a telephone, generally designated as 8, as is well known in the art. As the wiring of this type of station is conventional and since the electrical connections thereof form no part of the present invention, the subscriber's set is shown in conventional form with the wiring thereof omitted in the drawing.

Cooperating with this station is a mechanism generally designated as 3 for lifting the receiver from the stand and a message recording and repeating means generally designated as 4.

Cylindrical records 10 and 11 may, as will be apparent, separate and distinct or a single record, and, in the preferred embodiment of the invention, comprises impressionable wax cylinders. 20 These cylinders are positioned upon and revolved with a spindle 9 mounted upon a shaft 12 driven by motor 13. A drive pinion 14 is fixed to shaft 12.

A reproducer 15 is provided with a driving connection to a threaded shaft 16 to which is fixed a drive gear 17. A tension spring 19 is attached to reproducer 15 to return the reproducer to starting position when gear 17 is out of engagement with drive pinion 14.

A threaded extension 21 is attached to shaft 16 through a ratchet or over-running clutch 20 whereby the threaded extension is driven only when shaft 16 is rotated in such direction as will advance reproducer 15 along record 10. A 35 recorder 22 is connected to shaft extension 21 in a manner similar to the connection between shaft 16 and reproducer 15. It is apparent, however, that when shaft 16 is rotated by the retraction of the reproducer 15 under the influence of spring 40 19 shaft 21 will not rotate therewith because of connection 20 and hence recorder 22 remains at its advanced position and, as will be later explained, can be returned to its original position manually only.

A second threaded shaft 25 is positioned adjacent records 10 and 11 mounted on shaft 12 and is provided with a drive gear 26 affixed thereto. A reproducer 27 has a driving connection with shaft 25 and, similar to reproducer 15, is provided with a tension spring 28, which is adapted to return the reproducer to starting position when gear 26 is released from driving engagement with drive pinion 14. It will be apparent from the drawing that reproducer 27 is adapted to contact

the phonic grooves produced in cylinder 11 by recorder 22.

A microphone 30 is mounted upon support member 29 adjacent the receiver 6 of telephone 8 and is attached through conductors 31 and 32 to recorder 22 whereby an incoming message through receiver 6 may be recorded upon cylinder 11 under proper circumstances, as hereafter described. In a similar manner a speaker 33 is mounted upon support 29 adjacent transmitter 5 of telephone 8 and is connected through conductors 34 and 35 to a switch which is designated as 36.

Switch 36 is in effect a double-pole, double-throw switch adapted to connect speaker wires 34 and 35 to reproducer 15 when the armature thereof is retained in normal position by spring 36', as shown in the drawing. When, however, the switch is closed in the opposite direction by energization of solenoid 115 or solenoid 121, the speaker 33 is connected through wires 39 and 40 to reproducer 27. It is thus apparent that switch 36 may be instrumental in selectively transmitting to speaker 33 the message that is recorded on either of cylinders 10 and 11.

Support 29 is attached to the upper end of a rod 40 and this assembly is moved in a vertical direction by means of a motor 41 which drives a pinion 42 engaging rack teeth 43 on rod 40 to lift the microphone 30 and speaker 33 upwardly against the receiver 6 and transmitter 5 of telephone 8, thus lifting the receiver from the telephone stand 7 and answering a call. Rod 40 carries arms 44 and 45 which open and close switches 47 and 46, respectively, when the rod is elevated to raise the receiver from the stand. Attention is directed to the fact that switch 46 is normally held in closed position by a spring 48 while switch 47 is normally held open by spring 49.

A detent 51 is positioned adjacent rod 40 and is constantly urged by spring 52 to engage relation with a projection 50 on rod 40. The engagement of this detent with the lower face of projection 50 will take place when rod 40 is lifted a sufficient distance by motor 41 and rod 40 will in this manner be retained in its elevated position until detent 51 is retracted by the energization of solenoid 109.

Energy for the operation of the device of the invention is conducted thereto through terminals 60 and 61 which are indicated as positive and negative, respectively. This indication is used conventionally and hence it is understood that the device may be constructed for the use of either alternating current or direct current. It is also immaterial as to the source of this energy. The source may comprise the electrical circuits supplying energy to the residence or place of business of the subscriber; it may be a local source such as any battery or generator, or the device may be operated from central station batteries by supplying the energy to the device through telephone circuits.

Further description and the operation of the device is as follows:

In the two circuit telephone, as shown in the drawing, it is assumed that an answering record 10 and a recording cylinder 11 are in position to be driven by motor 13 and that a call is initiated to ringer 69 to cause clapper 70 to vibrate. A switch closing arm 71 is so located relative to clapper 70 as to be moved thereby to close the contacts of switch 72 which is ordinarily held open by a spring 73 when no current is flowing through the circuit. Upon the closure of switch

72 current flows through solenoid 79 to retain this switch in closed position. The circuit from negative terminal 61 includes wire 62, switch 72, solenoid 74, the contacts of switch 71, which are normally held in closed position by spring 78, conductor 63, switch 46 and motor 41 to the positive terminal 60. The energization of solenoid 74 opens the contacts of switch 75 which are normally held closed by spring 76. In view of the fact that the contacts of switch 75 are thus opened it is apparent that it is impossible for a second call to be initiated through the line to ringer 68 to defect the connection previously initiated through ringer 69. In using the invention it is obvious that arrangements may be made whereby a busy signal would be returned on the calling line when switch 75 is open.

The closure of the circuit just described by the actuation of the ringer 69 causes motor 41 to be energized and elevate rod 40 sufficiently to effect close engagement of the microphone 30 and the speaker 33 with the receiver 6 and transmitter 5 of telephone 8 and to lift the instrument from stand 7. Detent 51 moves under the lower face of projection 50 as switch 47 is closed and switch 48 is opened by arms 44 and 45. The initial circuit through motor 41 is thus broken and rod 40 tends to fall under gravity but is retained in its elevated position by the engagement of detent 51 with projection 50. The downward movement of rod 40 after switch 46 is opened is insufficient to permit opening of switch 47. For this reason a circuit is completed from negative terminal 61 through wire 90, switch 47 and wire 91 to motor 13, thence through contacts 93 and 94 of switch 95, which contacts are normally held in closed position by spring 96, to solenoid 97 and returning by way of conductor 118 to positive terminal 60. Energization of solenoid 97 causes shaft 16 to move inwardly and effect engagement of gear 17 with pinion 14 and at the same time to cause reproducer 15 and recorder 22 to contact cylinders 10 and 11, respectively. As cylinders 10 and 11 are driven by motor 13, which is energized by the current flowing through the circuit just described, reproducer 15 transmits to speaker 33 the message which was previously recorded thereon. In this manner the previously recorded message is transmitted through speaker 33 and over the telephone line to the calling station.

An example of a message that could appropriately be recorded upon cylinder 11 is: "This is L-6161 (owner's telephone number). The doctor is at present making a call. If you will please leave your name and number he will get in touch with you." The reproducer 15 would then travel along shaft 16 for a sufficient length of time for the caller to leave a reasonable message and would then repeat a recorded sign-off message such as, "Thank you, the doctor will call shortly". Just before closure of switch 100 by contact of projection 101 with armature 102 to overcome the tension of spring 103, which normally maintains switch 100 open. Closure of switch 100 energizes solenoid 109, the complete circuit being from negative terminal 61 through wires 90, 105 and 106, switch 100 and wire 107 to the positive terminal 60. Current flowing through this circuit causes withdrawal of detent 51 and allows rod 40 to drop, replacing receiver 2 upon stand 7 and opening the circuit through switch 47, which stops motor 13 and allows the reproducer on shaft 16 to return to its original position.

While the reproducer 15 has traveled along cylinder 10 as above described, the recorder 22 has

traveled along cylinder 11 to record any message that is picked up by microphone 30. As previously explained, when the incoming message is completed and the described circuits are de-energized the reproducer 15 is returned to its initial position under the influence of spring 19 but recorder 22 is permitted to remain in the position reached during the recording of the incoming message. Hence, if a succeeding incoming call were initiated through the line to ringer 69 the above described operations would be repeated and the succeeding message would be recorded on cylinder 11 in sequence after the preceding message or messages.

15 sage or messages. The owner of the device of the invention desiring to receive the calls taken during his absence calls in on the circuit to ringer 68 whereupon switch 110 is closed in a manner similar to the closure of the switch 72 just above described.

20 In this manner switch 110 is closed and solenoid 111 is energized to keep switch 110 closed against the tension of spring 112 which normally retains the switch in open position. Closure of switch 110 completes a circuit from negative terminal 61

25 through wire 62, switch 110, the contacts of switch 75 to solenoid 113 to open the contacts of switch 78, thereby preventing interference from an incoming call through ringer 69. From solenoid 113 current is carried through conductor 114 to solenoid 115 of switch 36, thence through solenoid 116 of switch 95 and wire 117 to switch 46 and motor 41 to positive terminal 60. Again motor 41 is energized to elevate rod 40 and lift the receiver 2 of telephone 8 from its stand, to open switch 46 and to close switch 47. When the circuit of motor 41 is opened solenoid 115 is de-energized and switch 36 will return to its original position were it not for a second solenoid 121 which is energized through a circuit as follows:

From negative terminal 61 current flows, as above explained, to motor 13, thence through switch contacts 94 and 96 of switch 95, to solenoid 121 and returning to the negative terminal 60 through solenoids 120 and 119 and wire 118. It is thus apparent that switch 36 will be retained in the upper contacting position while the armature of switch 95 will be held downwardly by solenoid 120. Solenoid 119 being energized by the same current, will draw shaft 25 inwardly to enmesh gear 26 and pinion 14 and to bring reproducer 27 into engagement with the phonic grooves previously engraved in cylinder 11. The message on cylinder 11 is repeated through speaker 33 to the calling party. When, however, this recorded message is completed spring contact 130 is forced into engagement with a fixed contact 131 on arm 132 fixed to recorder 22. Closure of contacts 130 and 131 close a circuit through solenoid 109 from negative terminal 61 through wire 90, switch 47, conductor 105, switch contacts 130 and 131, and wire 107 to the positive terminal 60. This releases rod 40, which drops under gravity, and the circuit is returned to position for receiving other incoming calls or repeating recorded messages. It is to be noted that recorder 22 remains in its last recording position until personal attention is given the instrument. Until such attention is accorded the device, it is obvious that other messages may be impressed upon cylinder 11 until the surface thereof is completely covered with recorded messages. At the same time it is apparent that the subscriber may call through the line to ringer 88 as often as desired and the device will in each

instance repeat all recorded messages on cylinder 11.

11. When it is desired to discontinue use of the device in connection with telephone 8 it is necessary only to disconnect the source of energy from terminals 60, 61. 5

It is obvious that a plurality of ringers may be provided with a plurality of switches 72 in parallel and that each of these ringers may be arranged to send a busy signal when the device of 10 the invention is sending or receiving messages.

It is believed that further description and operation of the device of the invention is unnecessary.

What is claimed is:

What is claimed is:

1. In a device for automatically responding to and repeating incoming telephone calls, a spindle, a motor adapted to drive said spindle, an impressionable wax record on said spindle, said record having an informing message portion and a portion adapted to receive an incoming message thereon, a reproducer to repeat the informing message, a recorder to be brought into recording relation with the receiving message portion of said record, a telephone, means actuated by an incoming call for lifting the receiver from its hook and for energizing said driving motor, means for transmitting the informing message to the transmitter of said telephone, means for transmitting the incoming message to said recorder, means for repeating the recorded message in answer to a subsequent incoming call, and means for deenergizing the device when the recorded message has been repeated.

corded message has been repeated.

2. In a device for automatically responding to and repeating incoming telephone calls, a spindle, a motor adapted to drive said spindle, an impressionable wax record on said spindle, said record having an informing message portion and a portion adapted to receive an incoming message thereon, a reproducer to repeat the informing message, a recorder to be brought into recording relation with the receiving message portion of said record, a telephone, means actuated by an incoming call for lifting the receiver from its hook and for energizing said driving motor, means for transmitting the informing message to the transmitter of said telephone, means for transmitting the incoming message to said recorder, and means operable by a subsequent incoming call for repeating the recorded message to the calling station.

3. In a device for automatically responding to and repeating incoming telephone calls, a spindle, a motor adapted to drive said spindle, an impressionable wax record on said spindle, said record having an informing message portion and a portion adapted to receive an incoming message thereon, a reproducer to repeat the informing message, a recorder to be brought into recording relation with the receiving message portion of said record, a telephone, means actuated by an incoming call for lifting the receiver from its hook and for energizing said driving motor, means for transmitting the informing message to the transmitter of said telephone, means for transmitting the incoming message to said recorder, and means operable by a subsequent incoming call over a different incoming line for repeating the recorded message to the calling station. 55 60 65 70

4. In a device for automatically responding to and recording incoming telephone calls, comprising a motor, a sound record to be driven thereby, a recorder adapted to be brought into recording 75

- relation with said record, a telephone, means actuated by an incoming call for lifting the receiver from its hook and for energizing said driving motor, means for transmitting the incoming message to said recorder whereby said message is recorded upon said record, and means for transmitting the recorded message in response to an incoming call. 5
5. An apparatus of the class described comprising a rotating spindle, an impressionable wax record thereon, means for driving said spindle, a drive pinion adapted to rotate with said spindle, a composite shaft adjacent said spindle and having an over-running clutch to connect the parts thereof, a drive gear on said shaft, a reproducer and recorder on the respective parts of said shaft, and means for bringing said gear and pinion into driving engagement and for bringing said reproducer and recorder in contact with said record. 10
10. An apparatus of the class described comprising a rotating spindle, an impressionable wax record thereon, means for driving said spindle, a drive pinion adapted to rotate with said spindle, a composite shaft adjacent said spindle and having an over-running clutch to connect the parts thereof, a drive gear on said shaft, a reproducer and recorder on the respective parts of said shaft, means for bringing said gear and pinion into 15 driving engagement and for bringing said reproducer and recorder in contact with said record, and means for de-energizing said driving means and for releasing said gear and pinion from driving engagement. 20
15. An apparatus of the class described comprising a rotating spindle, an impressionable wax record thereon, means for driving said spindle, a drive pinion adapted to rotate with said spindle, a composite shaft adjacent said spindle and having an over-running clutch to connect the parts thereof, a drive gear on said shaft, a reproducer and recorder on the respective parts of said shaft, means for bringing said gear and pinion into 25 driving engagement and for bringing said reproducer and recorder in contact with said record, and means for de-energizing said driving means and for releasing said gear and pinion from driving engagement. 30
20. An apparatus of the class described comprising a rotating spindle, an impressionable wax record thereon, means for driving said spindle, a drive pinion adapted to rotate with said spindle, a composite shaft adjacent said spindle and having an over-running clutch to connect the parts thereof, a drive gear on said shaft, a reproducer and recorder on the respective parts of said shaft, means for bringing said gear and pinion into 35 driving engagement and for bringing said reproducer and recorder in contact with said record, and means for de-energizing said driving means and for releasing said gear and pinion from driving engagement, and means for returning said reproducer to initial position. 40
25. An apparatus of the class described comprising a rotating spindle, an impressionable wax record thereon, means for driving said spindle, a drive pinion adapted to rotate with said spindle, a composite shaft adjacent said spindle and having an over-running clutch to connect the parts thereof, a drive gear on said shaft, a reproducer and recorder on the respective parts of said shaft, means for bringing said gear and pinion into 45 driving engagement and for bringing said reproducer and recorder in contact with said record, and means for de-energizing said driving means and for releasing said gear and pinion from driving engagement, and means for returning said reproducer to initial position. 50
8. In a device of the class described for automatically receiving and repeating incoming telephone calls the combination of a telephone, a plurality of ringers therefor, means responsive to the ringing impulses to one of said ringers for connecting the telephone to the calling line, means for recording the incoming message and means responsive to ringing impulses to another of said ringers for repeating the recorded message over the calling line to said last mentioned ringer. 55
9. In a device of the class described for automatically receiving, recording and repeating incoming telephone calls, the combination of means for receiving and recording a telephone message over an incoming line, and means operable by a call over a different incoming line for transmitting the recorded message to the calling station. 15
10. In a device of the class described for automatically receiving and repeating incoming telephone calls, the combination of means for transmitting a recorded answering message, means for receiving and recording an incoming message, means operable by a call over a different incoming line for transmitting the recorded message to the calling station, said answering and recording means being so constructed and arranged that a plurality of incoming calls may be sequentially answered and recorded. 20
11. In a sound reproducing and recording device a telephone, means responsive to all incoming calls for connecting the telephone to calling circuits, means responsive to certain predetermined incoming calls for transmitting a recorded answering message and for recording any incoming messages in sequence from the calling station, and means actuated by other predetermined incoming calls for transmitting all previous incoming messages to the calling station. 25
12. In a sound reproducing and recording device the combination of a telephone station, means responsive to an incoming call for transmitting an answering message and for recording incoming messages to the telephone station, and means operable by another call to the telephone station for transmitting in response to the last mentioned call, the previously recorded incoming messages. 30
